UNITED STATES PATENT OFFICE.

HARTFORD SWEET, OF BROOKFIELD, ILLINOIS.

IODIN-APPLICATOR.

1,332,859.

Specification of Letters Patent.

Patented Mar. 2, 1920.

Application filed April 1, 1918, Serial No. 225,995. Renewed June 2, 1919. Serial No. 301,351.

To all whom it may concern:

Be it known that I, HARTFORD SWEET, a citizen of the United States, residing at Brookfield, in the county of Cook and State 5 of Illinois, have invented a new and useful Iodin-Applicator, of which the following is a specification.

The invention relates to devices for holding and applying antiseptics, and particularly 10 tincture of iodin to wounds.

As is well known, tincture of iodin has been found to be the best all-around antiseptic for war surgery. Wounds treated with iodin in time are never known to develop 15 blood poisoning, lock jaw, gangrene, etc., but instead heal quickly and give a minimum of trouble. However, modern battle conditions are such as to force wounded men to lie sometimes for days without 20 surgical attention, with the result that their neglected wounds are in a most deplorable state before they reach a hospital. As a result, amputation, or even death is inevitable.

It is the primary purpose of this invention to provide an improved sealed iodin container of such small size that every soldier may carry one with his first aid kit into battle, and may open it easily and apply the iodin to his wound without need of 30 any special skill or instruction.

In order to fully understand the nature of the improvements, reference is made to the accompanying drawing, forming a part of this specification, in which:

35 Figure 1 is a full-sized elevation of one embodiment of the invention showing the containing tube inverted.

Fig. 2 is a like view showing it upright.

40 Fig. 3 is an enlarged longitudinal sectional view showing clearly the details of construction.

Fig. 4 is an elevation of the broken tube with its wick extending outwardly in readiness to apply the iodin to a wound.

45 Fig. 5 is a cross-section on the line 5—5 of Fig. 3; and

Fig. 6 is a perspective view of the wick or dauber removed from its casing.

Referring to the drawing, the numeral 10 50 designates a sealed casing or container, preferably of glass, which incloses a wick or dauber 11, made of some textile material and a quantity of tincture of iodin 12. While I prefer to use a special knitted 55 worsted material for the wick, any other class of textile goods may prove desirable,

such as cotton, silk, linen or mixtures, and I do not wish to be limited to my preferred wick material. The tube 10 is rounded at either end, as shown at 13, and is sealed as 60 14 indicates. At a point about two-thirds of the length of the tube from the sealed end 14, is a contraction 15, and in the narrowest part of this contraction is a filed circular incision 16. While the drawing shows 65 this incision to extend completely around the circumference of the tube, it will be obvious to those accustomed to handling glass tubing that such an incision is not necessary to make the tube break at the contraction, 70 and that by filing the tube deeply at one point only, the tube will be in condition to break along the line desired. However, to avoid ragged edges the incision should be as shown in the drawing.

75 The wick or dauber 11 as shown in the drawing, is made cylindrical and hollow and doubled walled providing a central longitudinal passage 18 between its cylindrical walls. The outside diameter of the wick is 80 such that it is held by friction within the walls of the tubular container 10, and does not shift its position when the latter is shaken. The double walls are formed by taking a hollow wick and doubling it on 85 itself much as one doubles a stocking, as will be readily understood, thereby forming an open end 19 and a closed end 20. Seated in the closed end 20 is a hollow retaining cylinder 17 of glass, or other desirable material. This cylinder is of slightly 90 less diameter than the contraction 15 of the tube. The cylinder 17 as a stiffener acts not only to retain the wick in the lower part of the tube when the upper part has been 95 broken off, but also acts as a convenient handle or grip for the wick or dauber when the user desires to remove the same from its casing and apply to a wound. The wick may be withdrawn from the tube, so that 100 the former may be used as a dressing.

The casing may be and preferably is enclosed in a protecting cylinder of wood or metal (not shown) to prevent breakage. About $1\frac{1}{2}$ or 2 cubic centimeters of tincture 105 of iodin are poured into the tube, a quantity sufficient to keep the wick saturated and to make sterile a very large wound. It is also planned to paste a label on the tube with printed direction for use, although the manner of employing the tube is considered 110 almost obvious. The user holds it in the

position of Fig. 2, breaks the tube at the contraction, and discards the upper end. The lower end (see Fig. 4) now holds all the tincture because the hollow wick allows the antiseptic to immediately flow to the end which is held lower. The wick projects for two-thirds of its length out of the container and is ready to act as a funnel by which medicament may be poured into the wound.

10 After the wound has been so treated, the wick may be pulled all the way out of its holder, and held at its closed end while the parts surrounding the wound are painted by iodin, and the cylinder 17 may then be removed from the wick and the latter may be laid against the wound to act as a temporary dressing.

While I have described one embodiment of my invention, I wish it to be distinctly understood that I contemplate making many changes and employing many modifications in practice. Thus, I do not intend to limit myself to a wick which is so placed as to extend two-thirds out of a tube when broken, nor do I desire to be limited to any particular form of handle for the wick. In some cases, it is contemplated that no handle at all may be used. Two wicks may be used in the same container if desired. Nor do I intend to use only the one form of glass tube illustrated. Besides, tincture of iodin, other antiseptics such as chlorinated eucalyptol, phenol, corrosive sublimate, etc., may be employed. I only wish to be limited by the appended claims, which collectively are regarded as the definition of my invention.

What is claimed is:—

1. An applicator for antiseptics comprising a sealed cylindrical container having a weakened portion and a hollow wick fitted within the container.
2. An applicator for antiseptic comprising a sealed glass tube having a weakened contraction, a medicament partly filling the tube, and a wick placed within the tube having a central passage for the medicament so that the latter is free to flow through the wick from one end of the tube to the other.
3. An applicator for medicaments comprising a sealed glass tube weakened at a point intermediate its ends whereby it may

be broken at said point, and a hollow wick within the tube so held that when the latter is broken the wick will have a portion of its length extending outside the tube, said wick 55 being removable as a unit from the tube and thereby capable of independent use.

4. An applicator for antiseptic solutions comprising a sealed glass container, weakened at an intermediate point, so that it may 60 be readily broken at said point, and a hollow wick within the tube so held that a portion of its length will extend without the tube when the latter has been broken, said wick being adapted to act as a funnel for 65 the solution.

5. An applicator for antiseptic solutions comprising a sealed frangible container, and a removable hollow double-walled wick within the container having a reinforcing 70 band placed between its walls at one end thereof.

6. An applicator for antiseptic solutions comprising a sealed frangible container, and a removable hollow double-walled wick 75 within the container.

7. An applicator for antiseptic solutions comprising a sealed glass container, said container having a weakened contraction in its walls intermediate the ends, a removable 80 hollow doubled-walled wick held within the tube, and a reinforcing cylindrical band held between the walls of the wick, said reinforcing band being of less diameter than the narrowest portion of the container.

8. An applicator for antiseptic solutions comprising a sealed frangible glass container, a hollow double walled wick of textile material held frictionally within the container, and a cylindrical band of glass 90 removably held between the folds of the wick at one end thereof, said wick being removable from the container and the band being adapted to act as a grip for the wick when so removed.

In testimony that I claim the foregoing as my own, I have hereto affixed my signature in the presence of two witnesses.

HARTFORD SWEET, M. D.
